Primary Examiner — Karen E Eldridge Powers*Assistant Examiner* — Margaret Leah Bryan(74) Attorney, Agent, or Firm — Tommy S F Wang; Wang IP Law Group, P.C.(57) CLAIM

The ornamental design for a flower shaped soap, as shown and described.

DESCRIPTION

FIG. 1 is a top, front and left side perspective view of my flower shaped soap, showing my new design;

FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.

The broken line portions of the flower shaped soap in FIGS. 1-5 and 7 represent unclaimed portions of the claimed design and form no part thereof.

1 Claim, 5 Drawing Sheets
